UNITED STATES PATENT OFFICE.

ARTHUR F. MILBRATH, OF MILWAUKEE, WISCONSIN.

MOUNTING FOR VALVE TAPPETS.

Application filed January 19, 1925. Serial No. 3,289.

This invention relates to improvements in mountings for valve tappets.

The objects of invention are to provide an improved mounting which may be readily removed and replaced, and which will have maximum efficiency and durability in service, and in which the alignments of the plungers will be preserved and normal spring pressures maintained after removal and replacement.

A specific object of this invention is to provide convenient means for the removal and replacement of the mountings by the simple operation of lifting the tappet rods 15 and removing a detachable section of the crank case or cam shaft casing to which the mountings are secured.

In the drawings:

Figure 1 is a vertical section of an internal combustion engine drawn generally to a plane which includes one of the crank shafts and one of the tappet rods.

Figure 2 is a fragmentary view drawn to the same plane but showing a modified form of construction.

Figure 3 is a plan view of a portion of a removable casing section and associated mountings of the type shown in Figure 1.

Figure 4 is an inner face view of the same.

Figure 5 is a sectional view drawn on line 5—5 of Figure 4.

Like parts are identified by the same reference characters throughout the several views.

The internal combustion engine illustrated in Figure 1 may be assumed to be of any ordinary type except as hereinafter specifically described. Each of the valve tappet rods 1 is extended through a relatively fixed spring seating 2 and the lower end is seated in a socketed plunger 4 having depending ears 5 in which a cam-actuated roller 6 is journaled. The cam shaft 7 is provided with a cam 8 for each valve tappet, said cam being operative upon the associated roller 6 to lift it at the proper time for opening the valve 10 in the usual manner. Compression springs 9 in the plunger sockets have their upper ends bearing against the seating 2 and these springs are therefore adapted to hold the rollers 6 in contact with their respective actuating cams.

The plunger 4 operates in a tubular guide

member 12 connected by an integrally formed bracket 13 with a detachable casing plate 14. The spring seating 2 is also connected with this bracket by bolts 16.

The plate 14 is connected with the body 20 of the casing by bolts 21, and as shown in Figures 1 and 2, this plate 14 is preferably elongated and adapted to cover a slot in the crank casing body wall 20 of sufficient length to allow access to the cam shaft throughout the area occupied by the cams. In such case all of the mountings—i. e.—the guide members 12, with their associated plungers, rollers and a channel shaped spring seating 2 common to all of the plungers and their springs, may be supported from a single plate 14 and removed therewith.

To remove the mountings, the valve actuating levers 25 will be depressed to open 75 all of the valves 10 and allow the tappet rods 1 to be removed. Thereupon the casing plate 14 may be unbolted and removed with a slight tilting movement which allows the mountings to be withdrawn 80 through the slot. Owing to the fact that all of the guide tubes 12 are supported from the plate 14 by connections which are either integrally formed or permanently connected with said plate, it is obvious that removals 85 and replacements of the mountings may be freely made without varying the adjustment or alignment of the parts.

In Figure 2 a plate 14^a is employed which is similar to that shown in Figure 1, but which is provided with a bracket 13^a supporting a tubular guide member 5^a which receives a plunger 30 in the upper end of which the valve tappet rod 1 is socketed. A foot plate 31 is connected with the lower end of the plunger 30 and is adapted to be actuated by the cam 8 to transmit motion to the associated plunger 30 and valve tappet rod 1. This plunger 30, with its foot plate 31, represents an ordinary type of valve tappet mechanism known commercially as the mushroom type as distinguished from the roller type illustrated in Figure 1. Further description thereof is, therefore, deemed unnecessary.

Owing to differences in the structure of internal combustion engines, and for the purpose of convenience in description, I refer to the body casing 20 as the cam shaft casing instead of designating it as a portion 110

2
of the crank case, although in the specific structure illustrated the plate 14 is employed to cover a slot in an offset portion of the crank case which receives the cam shaft and the valve tappet mountings. In the appended claims this portion of the casing body is therefore referred to as the cam shaft casing. It will also be understood that while I have illustrated and described the plate 14 as an elongated plate to which all of the valve tappet mountings are secured, it is not essential whether the plate is formed in one piece or in sections with each section supporting one or more of the mountings. The preferred embodiment of my invention comprises a single plate with all the mounting brackets permanently attached thereto or integrally formed therewith.

20 I claim—

1. The combination with an internal combustion engine having valve tappets and a cam shaft provided with tappet actuating means, of a slotted casing enclosing the cam shaft, cams and lower ends of the tappet rods; a plate adapted to close the slot in the cam shaft casing and provided with inwardly projecting brackets, tubular guides carried by the interior portions of said brackets, and tappet-actuating plungers mounted in said guides and adapted to be actuated by associated cams on the engine cam shaft.

2. The combination with an internal combustion engine having a cam shaft and valve actuating cams thereon, of a cam shaft casing provided with an opening in one wall adapted to afford access to all of the cams and associated portions of the valve actuating mechanism, a detachable plate adapted to be secured to the casing wall over said opening and guides for the lower portion of the valve actuating mechanism connected with said plate and bodily removable therewith, whereby said plate with the associated guides and portions of the valve actuating mechanism may be removed and replaced without changing their relative positions.

3. In a valve actuating mechanism, the combination with a plurality of valve tappet rods, of a set of guides for the lower end portion thereof, and a removable support for all of the guides of the set, adapted 55 to facilitate the simultaneous removal of all the guides and associated tappet members

and maintain tension adjustments and alignments upon replacement.

4. In a valve actuating mechanism, the combination with a plurality of valve tappet rods, of an enclosure for the lower end portions thereof having a removable section, and a set of guides for the tappet rods, each connected with said section and removable therewith.

5. In a valve actuating mechanism for internal combustion engines, the combination with a cam shaft and cams, of a cam shaft casing having a removable member provided with a guide supporting bracket, 70 plunger guides carried thereby in position for normal registry with the cams on the cam shaft, a channel shaped spring seating supported from said bracket and extending over the guides; said seating being apertured to receive tappet rods, coiled springs mounted in the guides with their upper ends bearing upon said seating, and cam actuated plungers also mounted in the guides with their upper ends bearing upon said 80 springs; said removable member, bracket, guides, seating, springs and plungers being bodily removable and replaceable as a unit, whereby upon such replacement the original 85 alignments and spring tension will be restored.

6. In a mounting for tappet actuating plungers, the combination with a set of permanently connected plunger guides, and a spring seating common to all the guides 90 and provided with apertures for the tappet rods, said seating being also permanently connected with the guides.

7. In a valve actuating mechanism, the combination with a plurality of valve tappet rods, of an enclosure for the lower end portions thereof having a removable section, a set of guides for the tappet rods secured to the removable section in fixed relation to each other, a spring seating cap member for 95 said guides, secured thereto and provided with bearing apertures for the tappet rods, and tappet actuating plungers seated in said guides, with compression springs interposed 100 between them and said spring seating cap member, whereby the guides, cap member and plungers may be removed with the casing section and replaced without alteration 105 in the original positions of the tappet rods and plungers.

ARTHUR F. MILBRATH.
